UNITED STATES PATENT OFFICE.

FREDERICK HAINSWORTH, OF CHICAGO, ILLINOIS.

REFRIGERATOR.

SPECIFICATION forming part of Letters Patent No. 331,296, dated December 1, 1885.

Application filed April 10, 1885. Serial No. 161,845. (No model.)

To all whom it may concern:

Be it known that I, FREDERICK HAINSWORTH, a citizen of the United States, residing in Chicago, in the State of Illinois, have invented a new and useful Improvement in Refrigerators, of which the following is the specification.

The object of this invention is to construct a refrigerator having the greatest amount possible of the interior shelf and wall surface in immediate contact with cold water, whereby all the interior of the refrigerator is kept uniformly cool.

Figure 1 is a perspective view, with two of the doors opened and certain other parts cut away. Fig. 2 is a vertical section through line *x x*, Fig. 1. Fig. 3 is a vertical section at right angles with Fig. 2. Fig. 4 is a cross-section through line *y y*, Fig. 2.

20 A is a water-space extending from the reservoir B down through the center to the bottom of the refrigerator, Fig. 4. From each side of this water-space A is a water-space extending from the reservoir B, through the center to 25 the bottom of the refrigerator. This water-space extends from side to side of the refrigerator. (See Fig. 4.) From each side of this water-space and connected with it are open shelves C C. Above this water-space is the 30 reservoir B, having apertures *a a* in the bottom, connecting with the water-space and open shelves. This system of open shelves is connected by water-joints at their ends to the side walls, D D, which constitute the inner walls 35 of the refrigerator, and between this inner wall D and the intermediate case, F, is the outer water-space, H.

E E is the outer casing.

F F is the intermediate casing of the refrigerator, leaving the air-space G between them.

40 I I are bolts extending through the open shelves C, and through the side walls, D D, having on one end a head and on the other a 45 nut and thread, which aids in holding firmly together the walls D D and shelves, and also greatly strengthens the refrigerator.

The two outer spaces, F F, are connected by

the hollow bolt Q, at or near the bottom. There may be one or more of these hollow 50 bolts. The open shelves C are at front and rear of water-space A, as shown in Fig. 3. These shelves are reached by drop-doors J J. Their manner of working is shown in Fig. 1. The doors are held in horizontal position by 55 jointed braces K. Cold water is placed in reservoir B, whence it passes into the water-space and open shelves below through the walls D D at *b b*, at or near the bottom, thence up the outer water-space, H, and out at the discharge-pipe L. This discharge-pipe L has its vertical arm extending downward in outer water-space, H, so the water will close the lower end and prevent air entering therein, and these two water-spaces being connected 60 by hollow bolt Q, the water is at the same height in all the water-spaces. In the reservoir is an ordinary water-trap, N, to govern the flow of water therein.

In this construction of a refrigerator I am 70 able to use cold water for cooling purposes, and the system of open shelves in connection with the central water-space, A, gives me the greatest amount of cooling-surface possible to be obtained. I can use ice also, when the drippings will fill the water-space below. The water can be drawn off through cocks O P, the lower one being for sediment, the upper one for clear water.

I claim—

1. A refrigerator provided with central water-space, A, and open shelves extending therefrom on opposite sides of central water-space, all communicating together, and also communicating with water-reservoir above, as 85 and for the purpose shown.

2. The combination of the open shelves C C, inner wall, H, and bolts I I, as and for the purpose shown.

3. In combination with a refrigerator, the 90 hollow bolts Q, to unite different water-spaces, substantially as shown.

FREDERICK HAINSWORTH.
